ABSTRACT

A terminal unit is provided with a plate-like terminal having a tip side extending in a first direction and a protecting member to be fixed to the tip side of the terminal. The terminal includes a first tip part and claw engaging portions. The protecting member includes a protecting body portion formed with an insertion recess, into which the first tip part is inserted, arm portions extending in a second direction from the both sides in the width direction of the protecting body portion and claw portions projecting toward each other from second tip parts of a pair of the arm portions. The protecting member is fixed to the terminal by fitting the claw portions into the claw engaging portions with the first tip part inserted in the insertion recess. The arm portions extend from an end part of the protecting body portion on the first direction side.

TERMINAL UNIT WITH IMPROVED PROTECTION

CROSS REFERENCE TO RELATED APPLICATIONS

This application is a national phase of PCT application No. PCT/JP2021/028731, filed on 3 Aug. 2021, which claims priority from Japanese patent application No. 2020-168838, filed on 6 Oct. 2020, all of which are incorporated herein by reference.

TECHNICAL FIELD

The present disclosure relates to a terminal unit.

Background

Conventionally, a vehicle such as a hybrid vehicle or electric vehicle is provided with in-vehicle devices such as a high-voltage battery and an inverter. The in-vehicle devices are connected via a wiring harness and connectors. Since there is a possibility of an electric shock if the tips of male terminals provided in such connectors touch a finger or the like, electric shock preventive measures are taken for some of the male terminals. The male terminals, for which the electric shock preventive measures are taken, include a terminal unit provided with a terminal made of a metal plate material and extending in a first direction and a protecting member made of an insulating material and fixed to a tip side of the terminal (see, for example, Patent Document 1 (FIG. 12 and the like)). This protecting member includes a protecting body portion formed with an insertion recess, into which the tip part of the terminal is inserted, arm portions extending in a second direction opposite to the first direction from both sides in a width direction of the protecting body portion and claw portions projecting toward each other from tip parts of the arm portions. Further, the terminal includes claw engaging portions, which are recessed from the width-wise sides and into which the claw portions are fit. The protecting member is fixed to the terminal by fitting the claw portions into the claw engaging portions with the tip part of the terminal inserted in the insertion recess.

PRIOR ART DOCUMENT

Patent Document

Patent Document 1: WO 2020/003566 A1

SUMMARY OF THE INVENTION

Problem to be Solved

However, in the terminal unit as described above, the arm portions need to be deflected in assembling the protecting member with the terminal and there has been a problem that a large stress is applied particularly to base end parts of the arm portions and the arm portions are easily broken when the arm portions are deflected.

The present disclosure was developed to solve the above problem and aims to provide a terminal unit capable of suppressing the damage of a protecting member.

Means to Solve the Problem

The present disclosure is directed to a terminal unit with a plate-like terminal having a tip side extending in a first

2

direction, and a protecting member to be fixed to the tip side of the terminal, a direction orthogonal to the first direction and a plate thickness direction of the terminal being a width direction, the terminal including a first tip part, the first tip part being an end part on a first direction side, and claw engaging portions recessed from both sides in the width direction, the protecting member including a protecting body portion formed with an insertion recess, the first tip part being inserted into the insertion recess, arm portions extending in a second direction opposite to the first direction from the both sides in the width direction of the protecting body portion and claw portions projecting toward each other from second tip parts to be fit into the claw engaging portions, the second tip parts being end parts of a pair of the arm portions on a second direction side, the protecting member being fixed to the terminal by fitting the claw portions into the claw engaging portions with the first tip part inserted in the insertion recess, and the arm portions extending from positions more on the first direction side than an end part of the protecting body portion on the second direction side.

Effect of the Invention

According to the terminal unit of the present disclosure, it is possible to suppress the damage of the protecting member.

BRIEF DESCRIPTION OF THE DRAWINGS

FIG. 1 is a perspective view showing a connector in one embodiment.

FIG. 2 is a partial plan view of a terminal unit in the embodiment.

FIG. 3 is an exploded perspective view of the terminal unit in the embodiment.

FIG. 4 is a section along 4-4 of FIG. 2.

FIG. 5 is a partial plan view showing the assembling of the terminal unit in the embodiment.

DETAILED DESCRIPTION TO EXECUTE THE INVENTION

Description of Embodiments of Present Disclosure

First, embodiments of the present disclosure are listed and described.

[1] The terminal unit of the present disclosure is provided with a plate-like terminal having a tip side extending in a first direction, and a protecting member to be fixed to the tip side of the terminal, a direction orthogonal to the first direction and a plate thickness direction of the terminal being a width direction, the terminal including a first tip part, the first tip part being an end part on a first direction side, and claw engaging portions recessed from both sides in the width direction, the protecting member including a protecting body portion formed with an insertion recess, the first tip part being inserted into the insertion recess, arm portions extending in a second direction opposite to the first direction from the both sides in the width direction of the protecting body portion and claw portions projecting toward each other from second tip parts to be fit into the claw engaging portions, the second tip parts being end parts of a pair of the arm portions on a second direction side, the protecting member being fixed to the terminal by fitting the claw portions into the claw engaging portions with the first tip part inserted in the insertion recess, and the arm portions

extending from positions more on the first direction side than an end part of the protecting body portion on the second direction side.

According to this configuration, since the arm portions extend from the positions more on the first direction side than the end part of the protecting body portion on the second direction side, the arm portions are longer as compared to the case where the arm portions extend from the end part of the protecting body portion on the second direction side. Thus, the arm portions are easily deflected. Therefore, even if the arm portions are deflected, for example, in fixing the protecting member to the terminal, it can be suppressed that a large stress is applied particularly to base end parts of the arm portions. Hence, the damage of the protecting member can be suppressed.

[2] Preferably, the arm portions extend from an end part of the protecting body portion on the first direction side.

According to this configuration, since the arm portions extend from the end part of the protecting body portion on the first direction side, the arm portions are longer as compared to the case where the arm portions extend from positions between the end part on the first direction side and the end part on the second direction side of the protecting body portion. Thus, the arm portions are more easily deflected. Therefore, even if the arm portions are deflected, for example, in fixing the protecting member to the terminal, it can be suppressed that a large stress is applied particularly to the base end parts of the arm portions. Hence, the damage of the protecting member can be more suppressed.

[3] Preferably, the protecting member has protecting member inclined surfaces facing each other, a width between the protecting member inclined surfaces being gradually reduced toward the insertion recess.

According to this configuration, since the protecting member has the protecting member inclined surfaces facing each other, the width between which is gradually reduced toward the insertion recess, the tip part of the terminal is smoothly inserted into the insertion recess by being guided by the protecting member inclined surfaces in assembling the protecting member with the terminal. Therefore, assembling is facilitated.

[4] Preferably, the terminal has terminal inclined surfaces, a width between the terminal inclined surfaces being gradually reduced toward the first tip part.

According to this configuration, since the terminal has the terminal inclined surfaces, the width between which is gradually reduced toward the first tip part, tip parts of the arm portions are smoothly deflected outward in the width direction, in other words, toward sides away from each other, by being guided by the terminal inclined surfaces in assembling the protecting member with the terminal. Therefore, assembling is facilitated.

[5] Preferably, the terminal inclined surfaces are disposed between the claw engaging portions and the first tip part.

According to this configuration, the protecting member can be smoothly assembled with the terminal because of such a positional relationship that the terminal inclined surfaces are disposed between the claw engaging portions and the first tip part.

[6] Preferably, the first tip part includes a press-fit portion to be press-fit into the insertion recess.

According to this configuration, since the first tip part includes the press-fit portion to be press-fit into the insertion recess, the rattling of the protecting body portion with respect to the terminal is suppressed and, eventually, the detachment of the protecting member from the terminal is suppressed.

Details of Embodiment of Present Disclosure

A specific example of a terminal unit of the present disclosure is described below with reference to the drawings. 5 Some of components may be shown in an exaggerated or simplified manner for the convenience of description in each figure. Further, a dimension ratio of each part may be different in each figure. "Parallel" and "orthogonal" in this specification mean not only strictly parallel and orthogonal, 10 but also substantially parallel and orthogonal within a range in which functions and effects in this embodiment are achieved. Note that the present invention is not limited to these illustrations, but is represented by claims and intended to include all changes in the scope of claims and in the 15 meaning and scope of equivalents.

Configuration of Connector 11

As shown in FIG. 1, a connector 11 is provided with a 20 connector housing 12 and a plurality of terminal units 13 fixed in the connector housing 12. The connector 11 is provided in a vehicle. For example, the vehicle is provided with in-vehicle devices such as a high-voltage battery and an inverter, and those in-vehicle devices are connected via a 25 wiring harness. The connector 11 is provided as a component for connecting the in-vehicle device and the wiring harness.

The connector housing 12 includes tubular portions 12a open to outside. The terminal unit 13 is so provided that a tip side thereof is exposed to outside through an opening of the tubular portion 12a while being accommodated in the connection housing 12. In this embodiment, two tubular portions 12a and two terminal units 13 are provided.

Configuration of Terminal Unit 13

As shown in FIGS. 1 to 4, the terminal unit 13 is provided with a terminal 21 and a protecting member 22. The terminal 21 is plate-like. The terminal 21 is made of a metal plate material. A tip side of the terminal 21 extends in a first direction X1. The terminal 21 is so arranged that the first direction X1, which is an extending direction of the tip side, coincides with an outward direction from the opening of the tubular portion 12a. The protecting member 22 is made of an insulating material. In particular, the protecting member 22 is made of an insulating resin material. The protecting member 22 is fixed to the tip side of the terminal 21, i.e. a 40 first direction X side of the terminal 21.

Configuration of Terminal 21

The terminal 21 includes claw engaging portions 21a recessed from both widthwise sides on the tip side thereof. Note that a width direction Y is a direction orthogonal to the 55 first direction X1, in which the terminal 21 extends, and a plate thickness direction Z of the terminal 21. Further, the terminal 21 includes a narrow portion 21b on a side closer to the tip than the claw engaging portions 21a. The narrow portion 21b is wider than a width between the claw engaging portions 21a and narrower than a base end side of the terminal 21.

Further, the terminal 21 has terminal inclined surfaces 21d on a side closer to the tip than the narrow portion 21b. A width between the terminal inclined surfaces 21d is gradually reduced toward a first tip part 21c, in other words, in the 60 first direction X1. The terminal inclined surfaces 21d are disposed between the claw engaging portions 21a and the

first tip part **21c**. Note that the first tip part **21c** is an end part on the first direction **X1** side of the terminal **21**. The first tip part **21c** of the terminal **21** is formed to extend with a constant width in the first direction **X1** from the tips of the terminal inclined surfaces **21d**.

Further, as shown in FIG. 4, the first tip part **21c** of the terminal **21** is so provided that there are steps between both end surfaces **21e** in the plate thickness direction **Z** and both end surfaces **21f** in another part of the terminal **21**, and a plate thickness thereof is set to be smaller than that of the other part.

Note that, as shown in FIG. 3, the base end side of the terminal **21** of this embodiment is bent. Further, a base end part **21g** of the terminal **21** is formed with a connection hole **21h**. An unillustrated harness is connected to the base end part **21g** of the terminal **21** via a bolt or the like passed through the connection hole **21h** and threadably engaged with a nut.

Configuration of Protecting Member 22

The protecting member **22** includes a protecting body portion **22a**, arm portions **22b** and claw portions **22c**. The protecting body portion **22a**, the arm portions **22b** and the claw portions **22c** are integrally molded. That is, the protecting member **22** is an integrally molded product.

The protecting body portion **22a** is formed into a substantially rectangular parallelepiped shape. In the protecting body portion **22a**, an insertion recess **22d**, into which the first tip part **21c** of the terminal **21** is inserted, is formed on a second direction **X2** side opposite to the first direction **X1** side. A width of the insertion recess **22d** is set to be slightly smaller than that of the first tip part **21c** in a state before the first tip part **21c** of the terminal **21** is inserted. In this way, the first tip part **21c** of the terminal **21** serves as a press-fit portion to be press-fit into the insertion recess **22d**.

Further, in the protecting body portion **22a**, projecting portions **22e** projecting in the second direction **X1** are provided on both sides in the width direction on the second direction **X2** side. A pair of the projecting portions **22e** are provided with protecting member inclined surfaces **22f**. A width between the protecting member inclined surfaces **22f** facing each other is gradually reduced toward the insertion recess **22d**.

The arm portions **22b** extend in the second direction **X2** from the both sides in the width direction of the protecting body portion **22a**. The arm portions **22b** extend from positions more on the first direction **X1** side than an end part of the protecting body portion **22a** on the second direction **X2** side. In particular, the arm portions **22b** of this embodiment extend from an end part of the protecting body portion **22a** on the first direction **X1** side. The arm portion **22b** includes an outward extending portion **22g** slightly extending outward in the width direction **Y** first from the widthwise side of the protecting body portion **22a** and an arm body portion **22h** extending in the second direction **X2** from the tip of the outward extending portion **22g**. The arm body portion **22h** is provided to form a small gap between the protecting body portion **22a** and the arm body portion **22h** in the width direction **Y**.

The claw portions **22c** project toward each other from second tip parts **22j**, which are end parts of the pair of arm portions **22b** on the second direction **X2** side. The pair of claw portions **22c** are provided with claw portion inclined surfaces **22k**. A width between the claw portion inclined surfaces **22k** facing each other is gradually reduced toward

the first direction **X1** side. The claw portions **22c** are formed to be fit into the claw engaging portions **21a** of the terminal **21**.

The protecting member **22** is fixed to the terminal **21** by fitting the claw portions **22c** into the claw engaging portions **21a** with the first tip part **21c** of the terminal **21** inserted in the insertion recess **22d**.

Next, functions of the terminal unit **13** configured as described above are described.

As shown in FIG. 5, as the protecting member **22** is moved in the second direction **X2** with respect to the terminal **21** in assembling the protecting member **22** with the terminal **21**, the second tip parts **22j** of the arm portions **22b** are guided together with the claw portions **22c** by the terminal inclined surfaces **21d**, thereby being deflected outward in the width direction **Y**. As the protecting member **22** is further moved in the second direction **X2** with respect to the terminal **21**, the first tip part **21c** of the terminal **21** is inserted into the insertion recess **22d** and the claw portions **22c** are fit into the claw engaging portions **21a**, whereby the protecting member **22** is fixed to the terminal **21**.

Next, effects of the above embodiment are described below.

(1) Since extending from the positions more on the first direction **X1** side than the end part of the protecting body portion **22a** on the second direction **X2** side, the arm portions **22b** are longer as compared to the case where the arm portions **22b** extend from the end part of the protecting body portion **22a** on the second direction **X2** side. Thus, the arm portions **22b** are easily deflected. Therefore, even if the arm portions **22b** are deflected in fixing the protecting member **22** to the terminal **21**, it can be suppressed that a large stress is applied particularly to base end parts of the arm portions **22b**. Hence, the damage of the protecting member **22** can be suppressed.

(2) Since extending from the end part of the protecting body portion **22a** on the first direction **X1** side, the arm portions **22b** are longer as compared to the case where the arm portions **22b** extend from positions between the end part on the first direction **X1** side and the end part on the second direction **X2** side of the protecting body portion **22a**. Thus, the arm portions **22b** are more easily deflected. Therefore, even if the arm portions **22b** are deflected in fixing the protecting member **22** to the terminal **21**, it can be suppressed that a large stress is applied particularly to the base end parts of the arm portions **22b**. Hence, the damage of the protecting member **22** can be more suppressed.

(3) The protecting member **22** has the pair of protecting member inclined surfaces **22f**, the width between which is gradually reduced toward the insertion recess **22d**. Thus, in assembling the protecting member **22** with the terminal **21**, the first tip part **21c** of the terminal **21** is smoothly inserted into the insertion recess **22d** by being guided by the protecting member inclined surfaces **22f**. Therefore, assembling is facilitated.

(4) The terminal **21** has the terminal inclined surfaces **21d**, the width between which is gradually reduced toward the first tip part **21c**. Thus, in assembling the protecting member **22** with the terminal **21**, the second tip parts **22j** of the arm portions **22b** are smoothly deflected outward in the width direction **Y**, i.e. toward sides away from each other, by being guided by the terminal inclined surfaces **21d**. Therefore, assembling is facilitated.

(5) By such a positional relationship that the terminal inclined surfaces $21d$ are disposed between the claw engaging portions $21a$ and the first tip part $21c$, the effect described in (4) described above can be obtained and the protecting member 22 can be smoothly assembled with the terminal 21 . 5

(6) The claw portions 22 have the claw portion inclined surfaces $22k$, the width between which is gradually reduced in the first direction $X1$. Thus, in assembling the protecting member 22 with the claw portion 22 , the second tip parts $22c$ of the arm portions $22b$ are smoothly deflected outward in the width direction Y , i.e. toward the sides away from each other, by being guided by the claw portion inclined surfaces $22k$. Therefore, assembling is facilitated. 10

(7) Since the first tip part $21c$ of the terminal 21 includes the press-fit portion to be press-fit into the insertion recess $22d$, the rattling of the protecting body portion $22a$ with respect to the terminal 21 is suppressed and, eventually, the detachment of the protecting member 22 from the terminal 21 is suppressed. 15

This embodiment can be modified and carried out as follows. This embodiment and the following modifications can be carried out in combination without technically contradicting each other. 20

Although the arm portions $22b$ extend from the end part of the protecting body portion $22a$ on the first direction $X1$ side in the above embodiment, there is no limitation to this and the arm portions 22 may be configured to extend from positions between the end part on the first direction $X1$ side and the end part on the second direction $X2$ side of the protecting body portion $22a$. Even if this configuration is adopted, an effect similar to the effect (1) of the above embodiment can be obtained. 25

Although the protecting member 22 has the pair of protecting member inclined surfaces $22f$ facing each other, the width between which is gradually reduced toward the insertion recess $22d$, in the above embodiment, there is no limitation to this. For example, the protecting member 22 may not include the protecting member inclined surfaces $22f$ and the projecting portions $22e$. 30

Although the terminal 21 has the terminal inclined surfaces $21d$, the width between which is gradually reduced toward the first tip part $21c$, in the above embodiment, there is no limitation to this. For example, the terminal 21 may not have the terminal inclined surfaces $21d$. 45

Although the claw portions $22c$ have the claw portion inclined surfaces $22k$ facing each other, the width between which is gradually reduced toward the first direction $X1$ side, in the above embodiment, there is no limitation to this. For example, the claw portions $22c$ may not have the claw portion inclined surfaces $22k$. 50

Although the first tip part $21c$ of the terminal 21 serves as the press-fit portion to be press-fit into the insertion recess $22d$ in the above embodiment, there is no limitation to this and the first tip part $21c$ may be inserted into the insertion recess $22d$ without being press-fit. Further, although the first tip part $21c$ serves as the press-fit portion to be press-fit into the insertion recess $22d$ while being pressed into contact with the insertion recess $22d$ in the width direction Y in the above embodiment, there is no limitation to this and the first tip part $21c$ may serve as a press-fit portion to be press-fit into the insertion recess $22d$ while being 55

pressed into contact with the insertion recess $22d$ in the plate thickness direction Z . The first tip part $21c$ may be modified into another configuration as long as including a part of the press-fit portion to be press-fit into the insertion recess $22d$. If the first tip part $21c$ includes the press-fit portion, the rattling of the protecting body portion $22a$ with respect to the terminal 21 can be suppressed. 60

Although the arm portion $22b$ includes the outward extending portion $22g$ slightly extending outward in the width direction Y first from the widthwise side of the protecting body portion $22a$ and the arm body portion $22h$ extending in the second direction $X2$ from the tip of the outward extending portion $22g$ in the above embodiment, the arm portion $22b$ may have another configuration. For example, the arm portion $22b$ may extend in an oblique direction to extend in the second direction $X2$ while extending outward in the width direction Y from the widthwise side of the protecting body portion $22a$. 65

Although the base end side of the terminal 21 is bent in the above embodiment, there is no limitation to this. For example, the base end side may be not bent. Further, although the base end part $21g$ of the terminal 21 is formed with the connection hole $21h$ in the above embodiment, there is no limitation to this and the base end part $21g$ may be shaped such that the connection hole $21h$ is not formed. 70

Although the connector 11 includes two terminal units 13 in the above embodiment, there is no limitation to this and the connector 11 may include only one terminal unit 13 or three or more terminal units 13 . 75

For example, as in the above embodiment, the width between the pair of arm portions $22b$ of the protecting member 22 may be equal to the width of the narrow portion $21b$ of the terminal 21 . 80

For example, as in the above embodiment, the width between the pair of projecting portions $22e$ of the protecting member 22 may be equal to or wider than the width of the first tip part $21c$ of the terminal 21 in the end part on the second direction $X2$ side. 85

For example, as in the above embodiment, the projecting portions $22e$ of the protecting member 22 may project in the second direction $X2$ from both sides in the width direction of the insertion recess $22d$. 90

For example, as in the above embodiment, an angle of inclination of the claw portion inclined surface $22k$ of the protecting member 22 with respect to a YZ plane may be equal to that of the terminal inclined surface $21d$ of the terminal 21 with respect to the YZ plane. In this case, in mounting the protecting member 22 on the terminal 21 , two claw portion inclined surfaces $22k$ separated in the Y direction can respectively come into surface contact with the two terminal inclined surfaces $21d$ of the terminal 21 . Thus, an inserting direction of the protecting member 22 to the terminal 21 is stabilized, wherefore the protecting member 22 can be smoothly assembled with the terminal 21 . 95

The terminal 21 in the shown embodiment can be manufactured, for example, from a metal plate having a first plate thickness. This first plate thickness may be a plate thickness between the end surfaces $21f$ of the terminal 21 . A plate thickness between the both end surfaces $21e$ of the first tip part $21c$ of the terminal 21 may be smaller than the first plate thickness and may be called a second plate thickness. For example, as shown in FIGS. 2 and 4, the terminal 21 may include a metal 100

plate body (both end surfaces 21f) having the first plate thickness and a tip part (first tip part 21c) having the second plate thickness smaller than the first plate thickness. The both end surfaces 21f of the terminal 21 may be called both end surface 21f of the metal plate body of the terminal 21. This metal plate body may be called a non-tip part except the first tip part 21c, out of the terminal 21. For example, as shown in FIG. 4, a maximum thickness (e.g. a thickness of the protecting body portion 22a) of the protecting member 22 in the plate thickness direction Z may be equal to the first plate thickness of the terminal 21.

For example, as shown in FIGS. 2 and 4, the insertion recess 22d of the protecting member 22 may be configured to entirely accommodate only the first tip part 21c of the terminal 21 with the protecting member 22 completely assembled with the plate-like terminal 21. For example, with the protecting member 22 completely assembled with the plate-like terminal 21, the protecting member 22 can cover the both end surfaces 21e of the first tip part 21c of the terminal 21 and the both end surfaces 21f of the metal plate body of the terminal 21 (non-tip part of the terminal 21) except the first tip part 21c of the terminal 21 may be exposed from the protecting member 22 without being covered by the protecting member 22.

LIST OF REFERENCE NUMERALS

11	connector
12	connector housing
12a	tubular portion
13	terminal unit
21	terminal
21a	claw engaging portion
21b	narrow portion
21c	first tip part
21d	terminal inclined surface
21e	end surface
21f	end surface
21g	base end part
21h	connection hole
22	protecting member
22a	protecting body portion
22b	arm portion
22c	claw portion
22d	insertion recess
22e	projecting portion
22f	protecting member inclined surface
22g	outward extending portion
22h	arm body portion
22j	second tip part
22k	claw portion inclined surface
X1	first direction
X2	second direction
Y	width direction
Z	plate thickness direction

What is claimed is:

1. A terminal unit, comprising:
a plate-like terminal having a tip side extending in a first direction; and
a protecting member to be fixed to the tip side of the terminal,
a direction orthogonal to the first direction and a plate thickness direction of the terminal being a width direction,
the terminal including a first tip portion, the first tip portion being an end portion on a first direction side, and claw engaging portions recessed from both sides in the width direction,
the protecting portion including a protecting body portion formed with an insertion recess, the first tip portion being inserted into the insertion recess, arm portions extending in a second direction opposite to the first direction from the both sides in the width direction of the protecting body portion and claw portions projecting toward each other from second tip portions to be fit into the claw engaging portions, the second tip portions being end portions of a pair of the arm portions on a second direction side,
the protecting portion being fixed to the terminal by fitting the claw portions into the claw engaging portions with the first tip portion inserted in the insertion recess, wherein each of the arm portions includes:
an outward extending portion extending outwardly in the width direction from the protecting body portion; and
an arm body portion extending in the second direction from the outward extending portion, and
a gap is defined, in the width direction, between the protecting body portion and each of the arm body portions.
2. The terminal unit of claim 1, wherein the arm portions extend from an end portion of the protecting body portion on the first direction side.
3. The terminal unit of claim 1, wherein the first tip portion includes a press-fit portion to be press-fit into the insertion recess.
4. The terminal unit of claim 1, wherein the outward extending portions extend from portions of the protecting body portion more on the first direction side than an end portion of the protecting body portion on the second direction side.
5. The terminal unit of claim 1, wherein the protecting portion has a pair of protecting inclined surfaces facing each other, a width between the protecting inclined surfaces being gradually reduced toward the insertion recess.
6. The terminal unit of claim 5, wherein the pair of protecting inclined surfaces are between the gaps defined between the protecting body portion and each of the arm body portions.
7. The terminal unit of claim 1, wherein the terminal has terminal inclined surfaces, a width between the terminal inclined surfaces being gradually reduced toward the first tip portion.
8. The terminal unit of claim 7, wherein the terminal inclined surfaces are disposed between the claw engaging portions and the first tip portion.
